(57) **CLAIM**

The ornamental design for a cover for air purifier, as shown and described.

DESCRIPTION

FIG. 1 is a front perspective view of a cover for air purifier, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view thereof, taken along line 8-8' of FIG. 6;

FIG. 9 is a front perspective view of the cover for air purifier in an alternate position;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is a cross-sectional view thereof, taken along line 16-16' of FIG. 14;

FIG. 17 is a front perspective view of the cover for air purifier in another alternate position;

FIG. 18 is a front view thereof;

FIG. 19 is a rear view thereof;

FIG. 20 is a left-side view thereof;

FIG. 21 is a right-side view thereof;

FIG. 22 is a top view thereof;

FIG. 23 is a bottom view thereof;

FIG. 24 is a cross-sectional view thereof, taken along line 24-24' of FIG. 22;

FIG. 25 is a front perspective view of the cover for air purifier in another alternate position;

FIG. 26 is a front view thereof;

FIG. 27 is a rear view thereof;

(Continued)

FIG. 28 is a left-side view thereof;
 FIG. 29 is a right-side view thereof;
 FIG. 30 is a top view thereof;
 FIG. 31 is a bottom view thereof; and,
 FIG. 32 is a cross-sectional view thereof, taken along line 32-32' of FIG. 30.
 The broken lines illustrating portions of the cover for air purifier form no part of the claimed design.
